UNITED STATES PATENT OFFICE.

BYRON A. SOULÉ, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,243,886.

Specification of Letters Patent. Patented Oct. 23, 1917.

Application filed January 25, 1917. Serial No. 144,343.

To all whom it may concern:

Be it known that I, BYRON A. SOULÉ, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to that type of mounting formed by the combination of two differing materials such as shell or xylonite and a metal whereby the strength of the metal is combined with the attractive appearance and comfortable qualities of the non-metallic member.

The principal object, therefore, of the present invention is the provision of novel and improved means for satisfactorily joining the several parts together in a simple, neat and attractive manner and insuring a firm union of the parts.

A further object of the present invention is the provision of means for the purpose above mentioned, which shall be so disposed as to be quickly applicable to the frame, and which will take care of any variance in the length of the parts as assembled.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Fig. I represents a front view of a mounting constructed in accordance with and embodying my improvements.

Fig. II represents a sectional view as on the line II-II of Fig. I.

Fig. III represents a fragmentary enlarged sectional view illustrating the attachment of the metallic and non-metallic parts.

Fig. IV represents a fragmentary perspective view of the joint.

Fig. V represents a perspective view of one form of end clip.

Fig. VI represents a sectional view through a slightly modified construction.

In the drawings, the numeral 1 designates

the bridge of an ophthalmic mounting provided at each end with the metallic rim or frame member 2 interiorly grooved to receive the usual lens 3. The frame members 2 are preferably split at their outer ends and provided with the end piece members 4 and 5 between which is pivoted a temple 6 for retaining the mounting in position on the face.

It will be understood that it is my desire to equip a mounting of these general characteristics with an improved ornamental preferably non-metallic shell or composition rim member 7, which shall add to the appearance of the mounting without appreciably increasing the weight thereof, and which will have extremely soft or pleasant feeling when contacting with the face of the wearer.

In the accomplishment of this result I preferably form the member 7 with the interior arcuate groove 8 to receive the frame member 2 and the beveled walls 9 adapted to fit against the lens substantially in the manner illustrated in Fig. II. It will thus be seen that the supplemental rim member 7 may be satisfactorily applied to an ordinary frame and on account of the fit of the frame within the groove it will only be necessary to secure the frame at its ends, where the same is split, corresponding to the regular frame, to facilitate the insertion or removal of a lens.

My improvement relates particularly to the manner of attachment of the construction at the ends, and should best be understood by reference to Figs. III and IV. By reference to these figures it will be seen that I have provided an improved cap member comprising the base or end wall 10 and the lateral upstanding tapering flange or side wall 11 forming a species of cup into which the end of the member 7 may fit, this cup being provided with an inwardly projecting lug or pin 12 to bite into and securely interlock with the supplemental frame member 7 to prevent relative longitudinal movement of the parts.

In use this cup member is applied to the end of the supplemental frame, as shown at the bottom in Fig. IV, and is provided with the screw threaded aperture 13 adapted to receive the screw 14 passing downwardly through the end piece 5 and into the base

- plate 10, whereby tightening of the screw will securely draw the supplemental frame down against the main frame and securely unite it in a substantially invisible manner 5 with the end piece, the side wall 11 if desired being somewhat clenched around the supplemental frame member 7 to aid the member 12 in securing the end of the supplemental frame member within the cup.
- 10 If desired to insure additional security of the parts the member 12 may be made sufficiently wide to allow the formation of a small screw threaded aperture therein adapted to receive the end of the securing 15 screw 14, in which event the aperture 13 is preferably plain or unthreaded and the screw co-operates directly with the plate 12 in the interior of the supplemental frame member, thus securely locking the member 20 12 in position and drawing it downward toward the end piece to insure tightest fit of the supplemental frame member 7 around the main frame, this construction being specifically illustrated in connection with Fig. 25 VI of the drawings.
- From the foregoing description taken in connection with the accompanying drawings, the construction and advantages of my improved device should be apparent, and 30 it will be seen that by its use I may quickly yet securely apply a supplemental frame member to an ordinary frame, may be sure of a satisfactory tight fit between the parts, as well as a neat and attractive connection 35 thereof, and may open or close the frame for insertion or removal of a temple, lens or the like as often as desired without in anywise disturbing the connection between the main and supplemental frames.

40 I claim:

1. The combination with a lens frame, of a supplemental frame encircling the main frame, end piece members carried by the main frame, caps carried by the ends of 45 the supplemental frame and means uniting

the caps on the supplemental frame with the end pieces of the main frame to secure the parts together.

2. The combination with a main lens frame having end piece members, of a supplemental frame encircling the main frame, and caps fitting and securely interlocking with the ends of the supplemental frame and engaging the outer faces of the end pieces, and means for detachably uniting the 55 caps and end pieces to retain the supplemental frame in position.

3. In a device of the character described, the combination with the lens frames split and provided with end pieces, of supplemental frames bearing terminal interiorly threaded plates and fastening devices extending through the end pieces and interlocking with the plates for securing the 60 parts together:

4. In a device of the character described, the combination with main and supplemental frames, of cap members carried by the supplemental frames and provided with interiorly threaded apertures, and fastening devices co-operating with said threaded apertures to secure the plates in desired relation, substantially as and for the purpose 70 described.

5. In a device of the character described, the combination with a lens frame provided with end pieces, of receptacles carried by the end pieces, a supplemental frame encircling the main frame and having its ends received within the receptacles, and means 75 for locking the ends within the receptacles 80 to secure the supplemental frame in position on the main frame.

In testimony whereof I affix my signature in the presence of two witnesses.

BYRON A. SOULE.
